UNITED STATES PATENT OFFICE.

ISAK WEISENFREIND, OF NEW YORK, N. Y., ASSIGNOR TO CENTURY SILVER MANUFACTURING COMPANY, OF NEW YORK, N. Y., A CORPORATION OF NEW YORK.

DESIGN FOR AN URN BODY.

Application filed April 12, 1926. Serial No. 17,266. Term of patent 3½ years.

To all whom it may concern:

Be it known that I, ISAK WEISENFREIND, a citizen of the United States of America, and resident of New York, county of New York, and State of New York, have invented a new, original, and ornamental Design for an Urn Body, of which the following is a specification, reference being had to the accompanying drawings, in which—

Figure 1 is a side elevation of an urn body, showing my new design; and—

I claim:

The ornamental design for an urn body, as shown.

ISAK WEISENFREIND.
